COMBINED ARCH SUPPORT AND HEEL CUSHION

Filed Nov. 14, 1927

Fig. 3

BY

INVENTOR.
George M. Schaff
Spofford, Maine

ATTORNEY.

UNITED STATES PATENT OFFICE.

GEORGE M. SCHAFF, OF CLEVELAND, OHIO.

COMBINED ARCH SUPPORT AND HEEL CUSHION.

Application filed November 14, 1927. Serial No. 233,198.

- The objects of the invention are to provide a cushioning and supporting attachment to a shoe that will enable the foot to rest in a natural and relaxed manner therein, without distortion of, or strain upon any part of the foot, thus permitting the foot to function in a natural manner and forming the shape of the shoe to the conformation of the foot.
- 10 The particular objects of the invention are to provide an improvement in cushion heels combined with an arch support for the arch of the foot, which is integrally formed with a hollow projection in one extremity that enters the heel.

This projection forms a cavity or recess that constitutes a seat or container for a resilient substance such as rubber, cotton or felt, that forms the cushion upon which the heel of the wearer rests.

This container being embedded in the heel of the shoe also serves to prevent the displacement of the cushion seated therein, and also serves as a fastening for the arch support. The device is also so designed as not to interfere with the construction of a standard shoe, and is of a simple and practical construction, and also adds little to the initial cost of the shoe.

30 The invention is hereinafter more fully described, illustrated in the accompanying drawings and specifically pointed out in the claims.

In the accompanying drawings Fig. 1, is a longitudinal section of the shoe showing the manner of placing the device in the shoe, Fig. 2, is a plan of the integral sheet metal container and arch support, Fig. 3, is a side elevation thereof, Fig. 4, is a plan of a modified form showing a lateral arch supporting attachment, Fig. 5, is an end elevation thereof, Fig. 6, is a transverse section of the cushion element.

In these views A, is the heel of the shoe, B, is the sole, C, is the instep, or arch.

The heel of the shoe is provided with a cavity D in its upper face in which is inserted the shallow container E, which is integrally connected with the spring arch support F, which lies under the arch of the foot, and is curved to correspond with the curvature, of the arch. This is adapted for use with either the right or left foot.

55 A cushion K, is provided with a part L, which is seated in this recess. The cushion extends over the arch F, and openings G, G,

may be made in the arch for the insertion of fastening nails, or screws if desired.

The insole H, covers the cushion and metal arch F from contact with the sole of the foot 60 and binds all the parts in place. As shown the flat portion of the cushion extends between the out sole and the lining or insole at the heel and the parts are secured by nails N outside the margin of the metal plate. 65

In Figs. 4 and 5 an upwardly curved lateral extension 1, is shown on the inner edge of the metal arch which is employed where the arch of the foot is unusually weak. This will be adapted for both the right and left 70 feet.

Nails J or other fastening means are employed to connect the sole, arch, cushion, and inner sole together.

Having described the invention what I 75 claim as new and desire to secure by Letters Patent is,

1. In combination, a shoe having a heel and a combined arch and heel cushion therefor, the latter comprising a sheet metal plate 80 extending over the arched portion of the shoe and over the heel said heel being provided with a recess, and said plate provided with a corresponding depression, the inner edge of said depression being flanged and provided with nail openings, said plate being also provided with nail openings, a cushion mounted upon the heel portion of said plate, said cushion having a projection entering the cavity in said plate, and also having a 85 laterally extended upper portion and a covering means for said cushion and sole and heel. 90

2. In combination, a shoe having a heel and a combined arch and heel cushion therefor, the latter comprising a sheet metal plate extending over the arched portion of the shoe and over the heel, said heel being provided with a recess, and said plate provided with a corresponding depression, the inner 95 edge of said depression being provided with nail openings, a cushion mounted upon the heel portion of said plate, said cushion having a projection entering the cavity in said plate, and also having a laterally extended upper portion and a covering means for said cushion and sole and heel, said covering means being secured to said heel and cushion, externally of the margin of said plate. 100 105

In testimony whereof I affix my signature.

GEORGE M. SCHAFF.
